UNITED STATES PATENT OFFICE.

WILLIAM IRELAN, OF OAK SPRINGS, IOWA.

SELF-ADJUSTING COUPLING FOR BRIDGE-CHORDS AND STAY-RODS.

SPECIFICATION forming part of Letters Patent No. 307,770, dated November 11, 1884.

Application filed April 7, 1884. (No model.)

To all whom it may concern:

Be it known that I, WILLIAM IRELAN, of 5
Oak Springs, in the county of Davis and State
of Iowa, have invented a Self-Adjusting Cou-
pling for Bridge-Chords and Stay-Rods, of which
the following is a specification.

My object is to prevent the dangers, acci-
dents, and loss of life and property occasioned
10 by the unequal expansion and contraction of
metal chords and rods in bridges, and their
consequent breaking, and the falling of bridges
when under heavy pressure of loaded wagons
and cars.

My invention consists in the construction
15 and combination of coupling-bars having pins
extending eccentrically from their opposite
ends with beams or rods having eyes at their
ends, as hereinafter fully set forth, in such a
manner that the bar will be turned by the ex-
20 pansion or contraction of any one beam or rod
connected therewith as required to produce
snug tight joints, to maintain an equal ten-
sion on all the connected rods and their ten-
sile strength combined, and to resist any strain
25 to which a chord or complete bridge may be
subjected.

Figure 1 of my accompanying drawings is a
side view of a section of a bridge, showing my
self-adjusting chord-coupling in use. Fig. 2
30 is a top view showing four beams adjustably
connected by means of one coupling-bar. Fig.
3 shows a section of chord in which eight rods
and beams are adjustably combined by means
of one of my coupling-bars. Jointly consid-
35 ered, these figures clearly illustrate the
construction and operation of my complete invention.

A is a metal bar, that has pins B projecting
40 from its opposite ends and on opposite sides
of the longitudinal axis of the complete re-
volving bar. The ends of the pins are screw-
threaded. By simply slipping the revolving
bar and its pins into the overlapping eyes of
metal beams, and then placing nuts on the

ends of the pins, the beams or rods required 45
to form a chord are adjustably connected in
such a manner that if they are not of exact
equal length or are subjected to unequal ex-
pansion or contraction the coupling-bar will
revolve a fractional part of a revolution, to 50
equalize the tension of all the beams or rods
connected therewith and relieve any one piece
of undue strain; and when all the pieces are
thus automatically adjusted and the complete
chord subjected to heat or cold it will lengthen 55
and shorten as required to maintain a uni-
form tension of all its pieces by the self-ad-
justing motions of the coupling-bars having
the pins on their ends eccentrically located
relative to the centers of motion of the com- 60
plete bars.

My coupling may be advantageously used
at the top or bottom of a bridge, or wherever
tension or stay rods are combined.

I am aware that a bolt or pin having a head 65
at one end and a screw at its opposite end has
had eccentrics on its body to engage the eyes
of rods, but not to fill the eyes, as required to
produce tight joints. My coupling-bar hav-
ing pins projecting from its opposite ends and 70
on the opposite sides of the longitudinal axis
of the bar, and adapted to fill the eyes of rods
and to secure snug tight joints in the complete
chord, is therefore novel and greatly advan-
tageous in connecting and adjusting four or 75
more beams or rods in a bridge.

I claim as my invention--

A coupling-bar, A, having pins B on its op-
posite ends and on the opposite sides of its
longitudinal axis, in combination with four 80
or more beams or rods having eyes at their
ends adapted to admit the said pins B, for the
purposes specified.

WILLIAM IRELAN.
